(57) **CLAIM**

The ornamental design for a frame, as shown and described.

DESCRIPTION

FIG. 1 is a top view of a frame showing my new design;

FIG. 2 is a bottom view thereof;

FIG. 3 is a left side view thereof;

FIG. 4 is a right side view thereof;

FIG. 5 is a front view thereof;

FIG. 6 is a rear view thereof;

FIG. 7 is a top, left and front perspective view thereof;

FIG. 8 is a top, right and front perspective view thereof; and,

FIG. 9 is a bottom and rear perspective view thereof.

The broken lines depict portions of the frame that form no part of the claimed design.

1 Claim, 9 Drawing Sheets
